DESIGN FOR WRAPPING PAPER OR THE LIKE

Ernest A. Messenger, Chicago, Ill., assignor to Consolidated Cosmetics, Chicago, Ill., a partnership composed of James L. Younghusband,
Howard Younghusband and Paul Rowatt

Application September 13, 1945, Serial No. 122,056

Term of patent 14 years

(Cl. D59—2)

To all whom it may concern:

Be it known that I, Ernest A. Messenger, a citizen of the United States of America, residing at Chicago, in the county of Cook and State of Illinois, have invented a new, original, and ornamental Design for Wrapping Paper or the like, of which the following is a specification, reference being had to the accompanying drawing, forming a part thereof.

Referring to the drawing the figure is a face view of wrapping paper or the like embodying my new design. The broken lines on the drawing outline a design unit, which unit is repeated over the wrapping paper as indicated by the extensions beyond the unit boundaries.

I claim:

The ornamental design for wrapping paper or the like, substantially as shown and described.

ERNEST A. MESSENGER.
